CLAIM

The ornamental design for a hinged U-block for packaging, as shown and described.

DESCRIPTION

FIG. 1 is a top, front, left perspective view of a hinged U-block for packaging shown in an unfolded configuration in accordance with the design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof;

FIG. 8 is a bottom, front, right perspective view of the hinged U-block for packaging of FIG. 1 shown in a folded configuration;

FIG. 9 is a rear view thereof;

FIG. 10 is a front view thereof;

FIG. 11 is a left side view thereof;

FIG. 12 is a right side view thereof;

FIG. 13 is a bottom view thereof; and,

FIG. 14 is a top view thereof.

The broken lines shown throughout the figures depict separable perforation lines that are part of the claim. The panel drawn with smaller broken lines in FIG. 8 represents environmental subject matter included to show the hinged U-block for packaging in a position of use and form no part of the claimed design.
